UNITED STATES PATENT OFFICE.

JOHN EMANUEL JOHNSON AND CHARLES H. OSLUND, OF WORCESTER, MASSACHUSETTS.

BOTTLE-CAPPING MACHINE.

Application filed October 31, 1919, Serial No. 334,683. Renewed September 28, 1925.

To all whom it may concern:

Be it known that we, JOHN EMANUEL JOHNSON and CHARLES H. OSLUND, citizens of the United States of America, residing at Worcester, county of Worcester, State of Massachusetts, have invented certain new and useful Improvements in Bottle-Capping Machines, of which the following is a specification.

10 Our invention comprises certain improvements on the apparatus shown and described in U. S. patent to Ernest A. Oliver, No. 1,310,960, dated July 22nd, 1919, and is designed to render the action of the same more uniform in certain particulars and to protect it from breaking strains when stoppages do occur as from caps jamming in the passage through which they are passing. The best form of apparatus at present known to us embodying our invention is illustrated in the accompanying two sheets of drawings in which,—

Fig. 1 is a side elevation of the machine.

Fig. 2 is an enlarged detail section of 25 the driving apparatus for the cap feeding mechanism.

Fig. 3 is a face view of the same, the hopper being removed and the shaft shown in cross section.

30 Fig. 4 is a section on line 4—4 of Fig. 2.

Fig. 5 is a detail view on an enlarged scale of the cap affixing mechanism, parts being broken away and others shown in section.

35 Fig. 6 is a similar side elevation of some of the parts shown in Fig. 5.

Fig. 7 is a side view of the cap delivering chute on an enlarged scale and of the cap affixing plunger, the latter being shown 40 partly in section.

Fig. 8 is a cross section on line 8—8 and Fig. 9 a cross section on line 9—9, of Fig. 7.

Fig. 10 is a horizontal section on broken 45 line 10—10 of Fig. 7.

Fig. 11 is a detail view of the cap feeder with parts broken away, and

Fig. 12 is a central vertical section of the machine.

50 Throughout the drawings like reference characters indicate like parts. As in the above mentioned patent to Oliver 1, represents the main frame of the machine on which is supported an approximately oval shaped table 2. This table has a rotating

section 3, located in a cylindrical opening at the center of the main table and this rotating table section is mounted on a vertical shaft 4, journaled in bearings 5, 6 and 7, carried by the main frame, the bearing 60 5 being a step bearing to support the shaft. The rotating table section 3, is keyed to shaft 4, by key 8, and supported and vertically adjusted by means of the nut 24, threaded on shaft 4, and these parts are rotated by the worm wheel 9, on shaft 4, engaging the worm 10, which is fast on the shaft of pulley 11. The pulley is driven by belt 12, from the electric motor 13, carried by the machine frame or, in any other 65 convenient manner.

According to our present invention, however the motor supporting frame or bed is hinged at one side to bracket 26, by hinge 27, and adjustably supported at the other 70 side by one or more set screws 29, each equipped with a lock nut 30.

The rotating table 3, has a series of pads 14, 14, set in its upper surface, equally spaced about the table center, of the proper size to receive the bottoms of a series of bottles. These pads are made of some elastic material so as to yield slightly when downward pressure is applied to the bottles. Over the rotating table 3, is the usual 80 star wheel employed in machines of this type which as shown is composed of a lower portion 15, and upper portion or plate 16, fastened to the sleeve on the lower portion by plate screws 17, 17, the latter being fastened to the supporting sleeve 21, by set screw 18. A second portion 19, of the star wheel consists of a ring with radial arms together constituting an outer section of the star wheel adjustable on the first described 85 section and fastened in any particular adjustment by set screw 20. The sleeve 21, which is on shaft 4, has a flange on its lower end through which pass screws 25, for fastening the sleeve to the table section 3. By 90 this construction the two sections of the star wheel may be adjusted circumferentially as a unit on the shaft so as to center the bottles received between the arms over the pads 14, and the part 19 of the star wheel can 95 be circumferentially adjusted on the part 15 to closely engage bottles of different diameters.

Above the table and star wheel is a rotating spider 54, which is keyed to the shaft 100 110

4, by a key 55, so as to rotate synchronously with the table and this spider is further supported by the upper section 22, of the vertical sleeve, which screws into the lower section 21, and is held in any desired position of adjustment therein by set screw 23.

The rotating spider 54, carries a series of capping plunger heads 56, which are vertically movable in the spider. These plungers have transverse stub shafts set in their upper ends. These shafts are arranged so as to lie radially to the main shaft 4, and on their inner ends carry beveled anti-friction rollers 59, resting on stationary beveled cam 64, which is carried by casting 63, from the cross head 65, which is vertically adjustable in the main frame by means of the bolt and set screw attachments 66 (Fig. 1), movable in slots 58 in said main frame. These short shafts 57, also carry anti-friction cylindrical rollers 60, and have intermediate flattened sections 61, which move up and down in slots 62, in an upwardly projecting sleeve from spider 54. As a result the capping plunger heads 56, are prevented from rotating on their axes and the beveled anti-friction rollers 59, are maintained in proper relation to the cam 64, on which they rest, thereby supporting the capping plunger heads. The lower portions of these plunger heads 56, are composed of internally cored, outwardly flaring guide sections 67, which are screwed into the lower ends of the plungers and thereby confine dies 68, between them and supporting washers 69, seated against shoulders in the internal recesses of the plungers. In these internal recesses and above the dies are mounted ejector plungers 70, normally forced down by springs 71, pocketed in the recesses of the plungers 56 and bearing against the collars 72, on ejector plungers 70. Each guide section 67 has an internal flange forming a support for the inserted bottle cap.

73, is a side slot in the guide section 67, through which a bottle cap 74, may pass from the cap chute 76, which engages the circumferential slot 75, in the spider 54, and registers with the slot 73, in each capping plunger head as it comes opposite. The means for feeding bottle caps to this chute 76, comprise the hopper 77, supported on the upper portion of the machine, and having in its lower portion a rotating hollow cap-feeding wheel 78, supported on horizontal shaft 79, which is rotated by means of beveled pinion 80, meshing with bevel gear 81, on shaft 4. By the operation of this mechanism the rotation of the table and main shaft 4, conveys motion to the hollow cap-feeding wheel 78, which tumbles the caps over until they drop into the radial spaces shown in Fig. 11 in the right position to drop down the chute 76, when coming opposite thereto, so that they are delivered

by this chute to the plunger heads 56 right side up.

As the machine operates, the plunger heads 56, are held by reason of the beveled rollers 59, running on the higher portions 70 of the cam 64, until any particular plunger approaches the pressure cam 82. The beveled roller then runs down into a depression in cam 64, so that the die 68, descends around the mouth of bottle 31 and forces the cap over the bottle mouth, as shown in Fig. 5, the die 68 crimping the edges of the cap down around the bottle mouth in the well known way. Normally this stage of operations occurs before the beveled roller reaches 80 the bottom of the depression in the cam 64, and thereupon the pressure cam 82, comes into action and positively drives the plunger head down a little further and, the collar 72, on ejector plunger 70, having come to a bearing on a second shoulder on the interior of plunger 56, the top of the cap is simultaneously flattened out by the end of said ejector plunger. Further motion of the table and spider 54, carries the whole assemblage of parts free from pressure cam 82, the plunger head 56, is lifted by cam 64, and the ejector spring 71, coming into action, drives down the ejector plunger 70, which clears the capped bottles from engagement 90 with the die 68, so that the bottle remains free upon the rotating table 3, and is carried around until it engages an ejector guide, not shown, by which it is removed from the rotating section of the table.

Obviously to avoid possible breakage of bottles the downward pressure of cam 82, must be a yielding pressure, although a considerable one. In the construction shown in Fig. 5, this pressure is primarily produced by a weight (not shown) on cam lever 83, said lever being pivoted at 84, so that it is free to rise and fall except as controlled by this weight or by a compression spring (also not shown) which bears upon the top of the 105 lever and is confined at its upper end.

To ensure the freeing of the capped bottle from die 68, in cases where it sticks in said die so tightly that spring 71, cannot force ejector plunger 70, down again when capping plunger 56 is freed from cam 82, and is lifted by cam 64, to the level shown in dotted lines in Fig. 5, we employ a knockout pin 32, which is loosely mounted in a hole bored 110 through capping plunger 56, so that its inner end rests on the upper end of the ejector plunger 70, while its outer end strikes flange or top-plate 33, on spider 54, when the capping plunger approaches the upper limit of its travel. This gives pin 32, a positive thrust 115 which knocks out ejector 70, and with it the capped bottle, no matter how tightly the latter may be stuck in die 68.

Another feature of our invention is concerned with the feeding of the caps to plunger 130

ers 56, ensuring as far as possible their regular delivery to properly centered position in guide block 67, and their harmless removal in case they are not correctly centered. For this purpose we give the chute 76 a swinging, spring supported mounting on arm 53 by means of yoke 38 supported by hinge 34 to its upper end and spring 35, bearing on yoke 36, carried by the lower end of arm 53. The position of chute 76 is adjusted against the pressure of spring 35, by adjusting screw 37. This renders the lower end of chute 76 capable of a slight movement away from slot 73 in the lower end of plunger 56, and ensures its being spaced back sharply against stop 37, when the force flexing the spring 35, is removed. If this action occurs just as each plunger capping head 56, comes into line with chute 76, the cap 74 in the lower end of the chute will be kicked or pitched with certainty through slot 73, into the cavity formed by the guide block 67 and die 68, so that the cap will be properly adjusted on the mouth of the bottle on which the capping plunger next descends. This properly timed "kick" of the chute is created by allowing cam roller 39 carried on the lower portion of chute 76 to drop into the depression in cam 40, formed on the outer face of guide block 67, as shown in Figs. 7 and 10.

Still another feature of our invention is concerned with the handling of the caps in hopper 77, avoiding breakage of the mechanism when a cap gets jammed in the hollow slotted wheel 78, and audibly calling the attention of the operator to the situation. These results are secured by a novel, friction driving mechanism by which motion is transmitted from shaft 79 to wheel 78. This comprises a gear 41 keyed on shaft 79, meshing with pinion 42, on one end of short shaft 43, which shaft is journaled in disc 44, loosely mounted on shaft 79, and carries on its other end projecting through disc 44, a shallow toothed gear wheel or friction wheel 45, engaged by spring 46, mounted on disc 44, at 47, and adjustable as to its pressure on gear 45 by screw 48, also carried by disc 44. This disc in turn drives hollow wheel 78, by means of pins 49, 49 set in bosses 50, 50, on the disc 44 and engaging holes in wheel 78. A cover 51, locks on disc 44, by bayonet point 52 (see Fig. 1) and protects the gearing on the outer surface of the disc. To remove the disc, the spring latch 85, shown in Figs. 2 and 4 is removed from engagement with the groove 86, around the end of the shaft 79. The disc 44 and the parts carried by it may then be pulled off the end of shaft 79. In operation the gear 41, pinion 42, shallow gear 45, and disc 44, are locked together by spring 46 so that they revolve with shaft 79, and the disc, by pins 49, rotates feed wheel 78. If, however,

a cap sticks in wheel 78, so as to stop it from rotation the spring 46, begins to slip and snaps over the teeth of gear or friction wheel 45, disc 44, standing still while gear 41, continues rotation and pinion 42, and gear 43 begin to rotate. The noise of the spring snapping over the shallow gear teeth immediately attracts the operator's attention so that he has time to grasp cover 51, and give the wheel 78 a backward whirl, or otherwise free the jammed cap and cause the feeding action to be resumed before the supply of caps in transit through chute 76, is exhausted. Consequently there need be no interruption in the bottle capping operation.

If, on the other hand, a cap jams at the mouth of chute 76, or is not fed all the way into the guide block 67, continued rotation of spider 54, forces such cap against swinging panel 87, pivoted to the side of the chute 85 at 88, and held in place by spring 89, attached to arm 90. This panel yields and allows the cap to escape. Spring finger 91, carried by panel 87, runs in groove 75, and holds the caps in the plungers 56 till they begin to descend to force them on the bottles beneath.

The general method of operation of the machine is as follows: The rotating table section 3, the star wheel and the spider 54, rotate continuously, bottles being fed to the star wheel and a capping head 56, being held above each bottle held in the star wheel. Each capping head, after passing the cap chute, has a cap in it, held in proper position over any bottle beneath it. Each capping head so equipped and having a bottle beneath it comes in its order under pressure cam 82, and is driven down to crimp the cap on the bottle as previously explained, the supporting cam 64 having a depression in it to permit of this. As each head passes under and clears the pressure cam 82, it is lifted by the supporting cam 64, frees itself from the capped bottle, and passes on around 110 to the cap chute again to receive another cap. The capped bottle remaining on the rotating table section 3, is carried around until it is removed by any suitable agency.

Tension of the driving belt 12 can be adjusted by screw 29 which swings motor 13 toward or from pulley 11.

Having described our invention we claim:

1. In a bottle capping machine the combination, with a reciprocating capping head having in its side an opening for the admission of a cap and a rotatable carrier for said head, of a chute for delivering a series of caps to said head movable toward and from the same, and means for giving the delivery end of said chute a quick motion toward and from the head while the head is in raised position and is being moved to carry the above mentioned opening circumferentially past the said delivery end.

2. In a bottle capping machine the combination, with a series of vertically reciprocating capping heads, each having in its side an opening for admission of a cap 5 and means for moving said heads horizontally, of a chute for delivering a series of caps, one to each of said heads as it comes opposite the lower end of the chute, a hinged support for the upper end of the chute, 10 yielding means tending to oscillate the lower end of the chute toward the capping head, and cams movable with the heads and bearing against the lower end of the chute adapted to force the chute outward, as each 15 capping head approaches it, and to allow it to be snapped inward as the opening in each head comes opposite the chute end. 3. In a bottle capping machine the combination with a capping head having an 20 opening in its side to admit a cap and an interior cap support therefor, a bottle support, and means for causing the capping head and bottle support to periodically approach toward and recede from one another, 25 of a swinging chute for delivering caps to the opening in the head, and separate means for periodically withdrawing the lower end of said chute and thereafter quickly snapping it back into position while 30 the head is held in raised position, whereby a cap located in the lower end of the chute is pitched through the side opening to the interior of the capping head into a position on the cap supporting portion of said head and in line with the bottle to which it is to be applied. 4. In a bottle capping machine the combination of the main frame, a revolving spider journaled therein, a series of capping heads mounted in said spider each having 35 a lateral opening for admission of a cap, a chute for delivering such caps hinged at its upper end to the main frame so as to be movable toward and from the heads, a spring supported by the frame bearing on the chute and tending to swing its lower end toward each passing head, and cam means operated by the revolving spider for 40 flexing the spring and reciprocating the chute toward and from the passing heads. 5. A structure such as set forth in claim 4, combined with an adjustable stop on the main frame adapted to limit the motion of the chute toward the spider. 6. In a bottle capping machine, in combination, a main shaft, a series of reciprocating capping heads mounted for movement about the axis of said shaft and each head having a cap receiving opening, a movably mounted chute to deliver caps to successive heads, and means to give the delivery end of said chute a quick movement toward and from a head, said movement being effected in fixed relation to the angular advance of said head about the axis of said 55 shaft. 7. In a bottle capping machine, the combination with cap affixing apparatus, a rotating cap delivering device and driving connections between said apparatus and said device including a rotated element, of a friction mechanism included in said connections and comprising a floating pinion mounted on a pivot fixed in said rotated element and displaced from the axis of rotation thereof, a friction wheel rotatable with said floating pinion, and yielding means also mounted on said rotated element and engaging said friction wheel to normally hold said wheel and said rotated element 60 from relative rotation. 8. In a bottle capping machine the combination, with cap affixing apparatus and a rotating cap delivering mechanism loosely mounted on a shaft geared to the cap affixing mechanism, of a disc connected to the cap delivering mechanism and concentric with the said shaft, a gear on the shaft, a pinion mounted and rotatable on the disc and meshing with the gear, and a spring 65 also mounted on the disc and adapted to exert a frictional resistance against rotation of the pinion on its axis, and to be audibly vibrated by any such rotation.

JOHN EMANUEL JOHNSON.
CHARLES H. OSLUND.
